HAND BAG

Herman B. Welch, Waukesha, Wis., assignor, by
mesne assignments, to Mastercraft Leather
Goods, Inc., a corporation of Wisconsin

Application August 12, 1932, Serial No. 628,458

6 Claims. (Cl. 150—34)

This invention relates to improvements in hand bags, and more particularly to hand bags equipped with movable inserts.

One of the objects of the present invention is 5 to provide a ladies' hand bag or the like equipped with a pocket enclosed combination coin purse and bill fold so connected with the hand bag within its pocket that it is normally completely enclosed and protected, but yet easily withdraw-
10 able to a position affording ready access to either the purse or bill fold without actual physical severance from the hand bag.

A further object of the invention is to provide 15 a combination bill fold and coin purse superim- posed on one another for use and reception in a pocket of a bag or larger receptacle.

A further object of the invention is to provide 20 in combination with a hand bag or the like, a combination bill fold and coin purse superim- posed on one another and having a slidable con- nection with a pocket of the bag.

A further object of the invention is to provide 25 in combination with a hand bag or the like, a combination bill fold and coin purse superim- posed on one another and accessibly but non- separably, slidably mounted within a pocket of the bag on a rigid connector.

A further object of the invention is to provide 30 a combination structure of the class described wherein the rigid connector on which the combination bill fold and coin purse is slidably mounted with respect to the hand bag, extends between adjacent walls or layers of the purse and bill fold portions respectively and is therefore 35 concealed and protected.

A further object of the invention is to provide 40 a non-severable coin and bill purse equipped hand bag which is of very simple construction, is strong and durable, is neat and attractive in appearance, is easily manipulated, and is well adapted for the purposes described.

With the above and other objects in view the invention consists of the improved hand bag and its parts and combinations as set forth in 45 the claims, and all equivalents thereof.

In the accompanying drawings in which the same reference characters indicate the same parts in all of the views:

Fig. 1 is a front view of one form of hand bag 50 embodying the invention with the cover or protecting flap released and raised;

Fig. 2 is a fragmentary view of the showing in Fig. 1 with the combination bill fold and coin purse non-severably moved partially out of its pocket for accessibility;

Fig. 3 is a detail view of the combination bill fold and coin purse taken from the side opposite to that shown in Fig. 2;

Fig. 4 is a detail transverse vertical sectional view taken on line 4—4 of Fig. 3;

Fig. 5 is a view similar to Fig. 2 only showing a modified form of connector for the bill fold and coin purse with respect to the bag;

Fig. 6 is a sectional view taken on line 6—6 of Fig. 5; and

Fig. 7 is a similar transverse vertical sectional view only showing the normal position of the bill fold and purse within its pocket of the bag and the consequent disposition of the connector.

Referring now more particularly to the drawings, it will appear that the numeral 10 indicates 15 a ladies' hand bag including a body portion 11 having therein the usual pockets or compartments 12. A cover flap 13 is adapted to be folded over the body portion to protect the pockets or 20 compartments and is secured in closed position against an outer wall 14 of the body portion by complementary fastening elements 15 and 16.

Insofar as the invention is concerned any of 25 the usual pockets of the hand bag 10 may be used, but for the purpose of illustration an additional pocket 17 has been incorporated in the wall 14 of the hand bag, and the open free end of said pocket is controlled by a slide fastener 18. The combination bill fold and coin purse, indicated generally by the numeral 19 is mounted 30 within said pocket, but it should be understood that the particular location for the pocket for the member 19 is optional.

The combination bill fold and coin purse 35 19 comprises a purse portion 20 of usual construction having a front wall 21. Also, the bill fold portion 22 consists of a sheet of material such as fabric, leather or composition of suitable proportions folded medially longitudinally upon itself. The 40 bill fold is connected against the face 21 of the purse by being secured along its upper edge to the top frame portion of the purse, and the lower edge of the same flap or ply of the bill fold is 45 stitched to the lower edge of the face 21 of the purse. However, in the form of the invention illustrated in Figs. 1 to 4 inclusive, the lower connection between the purse and bill fold is broken centrally with respect to the purse to 50 provide a slot 23.

Insofar as the form of the invention illustrated 55 in Figs. 1 to 4 inclusive is concerned, the combination bill fold and coin purse 19 is adjustably but non-severably connected to the hand bag within 55

the pocket 17 by a T-shaped, rigid connecting member 24. The head portion 24' of said connecting member is of greater dimensions than the slot 23 so as to prevent withdrawal through said slot, and said head portion is positioned in the space between the secured together walls of the purse and bill fold. The shank portion of said member 24 depends through the slot 23 and is positively secured at its lower end to the hand bag 10 within the pocket 17, as at 25.

The hand bag is carried and used in the normal manner and ordinarily the member 19 is completely housed within its pocket 17 and the pocket is closed by means of the slide fastener 18. Also, the entire hand bag is closed and protected by the flap 13 which is normally folded over and secured in place. If access to the member 19 is desired the hand bag is opened as is the pocket 17, and then the member 19 is bodily moved on the shank of the connector 24 to a position from that shown in Fig. 1 to a partially outwardly projecting and exposed position, as in Fig. 2. Further outward movement and severance is prevented by virtue of the attachment of the connector 24 with the hand bag and engagement of the head 24' of the connector with the bottom connection between the bill fold and purse. Access to either or both portions of the member 19 is thus afforded without the danger of losing the member 19 from its pocket.

In the form of the invention illustrated in Figs. 5 to 7 inclusive a different form of connector between the combination bill fold and coin purse, and the hand bag, is utilized. The construction of the other elements is the same as that previously described. In this form of the invention the coin purse 20, which is superimposed upon the bill fold 22, is provided with a depending flexible flap 26. The lower edge of said flap is stitched to an inner wall of the pocket 17, as at 27, and the length of said flap and the disposition of said line of stitching 27 a suitable distance above the bottom of the pocket is such that when the member 19 is in its normal lowered position (see Fig. 7) said flap 26 will fold neatly upon itself without bunching while when the member 19 is extended to an accessible position, as in Figs. 5 and 6, the securing of the flap prevents complete withdrawal and severance of the member 19.

From the foregoing description it will be seen that the improved hand bag is of simple and novel construction, and is well adapted for the purposes set forth.

55. What is claimed as the invention is:

1. The combination with a receptacle, of a combination bill fold and purse movably housed by said receptacle and comprising laterally adjacent purse and bill fold elements having peripheral portions of their adjacent faces connected together to provide a pocket therebetween, and a connector element movably extending into said pocket, there being complementary means formed on the purse and bill fold member and the connector element to prevent complete withdrawal of the connector from the pocket and consequent detachment of the purse and bill fold member from the connector.

2. In combination, a hand bag having a pocket therein, a combination bill fold and purse

normally completely housed by said pocket, said bill fold and purse comprising laterally adjacent purse and bill fold elements having peripheral portions of their adjacent faces connected together to provide a pocket therebetween, said pocket having an opening, and a rigid connector secured within the hand bag pocket and extending through said opening into the pocket between the faces of the bill fold and purse elements and permitting sliding, but non-detachable movement of the combination member with respect to said connector.

3. In combination, a hand bag having a pocket therein, a combination bill fold and purse normally completely housed by said pocket, said bill fold and purse comprising laterally adjacent purse and bill fold elements having peripheral portions of their adjacent faces connected together to provide a pocket therebetween, said pocket having an opening, and a rigid, elongated, flat T-shaped connector secured at the lower end of its shank portion within the pocket of said hand bag and having its shank portion extending slidably through the opening into the pocket between the faces of the bill fold and purse elements with the head of said T-shaped connector confined in said latter pocket and preventing complete withdrawal of the combination member from the connector when the former is moved relatively to the latter for partial ejection from the hand bag pocket.

4. A combination coin and bill holder, comprising a purse element and a laterally adjacent bill fold element, said elements having peripheral portions of their adjacent faces secured together to provide a pocket therebetween, and a connector strip relatively slidably attached to said combination member within said pocket and depending from said combination member for securement within a pocket of a hand bag to prevent severance of the combination member from the hand bag.

5. In combination, a hand bag having a pocket therein, a combination insert including a bill fold and purse normally completely housed by said pocket, said bill fold comprising a section of material folded on itself with both free ends of the section facing upwardly and said purse being secured to one side of the bill fold and also opening upwardly, and a rigid connector secured to an inner portion of the hand bag and relatively slidably engaged with the insert to provide for movement of the insert to a position of partial withdrawal from the pocket of the hand bag and preventing further withdrawal, the construction of the insert providing for accessibility to both the bill fold and purse while the insert is in said position of partial withdrawal.

6. The combination with a main receptacle, of a smaller receptacle having an opening and movably and non-severably housed by the main receptacle, and a rigid connector having one portion thereof secured to the main receptacle and having another portion thereof slidable with respect to the opening of the smaller receptacle and formed with a T-shaped head for limiting the movement of the small receptacle on said connector.
